REFUSE CONTAINER CARRIER

Hugh E. Cooper, Rochelle, Ill., assignor to Anson Tool and Manufacturing Company, Inc., Chicago, Ill., a corporation of Illinois

Filed Apr. 24, 1964, Ser. No. 79,678

Term of patent 14 years

(Cl. D14—3)

FIG. 1 is a perspective view of a refuse container carrier, showing my new design;

FIG. 2 is an elevational view of the left side of the carrier thereof the side opposite that shown in FIG. 1;

FIG. 3 is an end elevational view thereof, taken from the right of FIG. 2; and

FIG. 4 is a top plan view thereof.

The containers shown in broken lines in FIG. 1 are included for illustrative purposes only.

I claim:

The ornamental design for a refuse container carrier, as shown and described.
